UNITED STATES PATENT OFFICE.

WILLIAM S. SHARPNECK, OF CHICAGO, ILLINOIS, ASSIGNOR TO EVERETT W. BROOKS, OF CHICAGO, ILLINOIS.

ROTARY PUMP.

SPECIFICATION forming part of Letters Patent No. 730,052, dated June 2, 1903.

Application filed September 25, 1901. Serial No. 76,524. (No model.)

To all whom it may concern:

Be it known that I, WILLIAM S. SHARPNECK, a resident of Chicago, in the county of Cook and State of Illinois, have invented certain new and useful Improvements in Rotary Pumps, of which the following is a specification.

This invention relates to improvements in rotary pumps, and refers more specifically to improvements in pumps of that type described in reissued Letters Patent No. 12,001, granted to me June 17, 1902, and in which a hollow shell-like piston, provided internally with pallets or vanes, is rotated and operates to pump the liquid by the centrifugal action imparted thereto.

The present invention is in the nature of an improved and further development of an invention described and patented to me in Letters Patent No. 644,475, dated February 27, 1900; and the object of the present invention is to provide an improved construction in which the piston operates more effectively in producing an exhausting or sucking action and in which also the expelling action upon the liquid due to centrifugal force is added to by the expelling action due to direct impact of the blades or vanes of the piston upon the liquid.

The invention has also in view the production of an extremely simple, cheap, and durable construction.

To these ends the invention consists in the matters hereinafter described, and more particularly pointed out in the appended claims, and the same will be readily understood from the following description, reference being had to the accompanying drawings, in which—

Figure 1 is an axial and sectional view of a pump-head and connecting parts embodying a preferred form of my invention. Fig. 2 is a transverse sectional view taken on line 2 2 of Fig. 1 and looking in the direction of the arrows. Fig. 3 is an end view of the inlet end of the piston removed from its casing, the direction of rotation in operation being indicated by the arrow. Fig. 4 is a central transverse sectional view of the piston viewed in the same direction as in Fig. 3.

Referring to said drawings, 1 designates as

a whole the pump-casing, which is shown in the present instance as internally cylindric and constructed of two disk-like end castings 2 and 3, respectively, between which is interposed a cylindric shell or casting 4, the peripheries of the end castings 2 and 3 and the end margins of the cylindric shell being united by means of bolts 5, extended through outwardly flange portions 6 upon the shell member 4 and through corresponding parts of the peripheries of the end castings, as indicated clearly in the drawings. The end casting 2 is provided with an integral axially-disposed tubular extension 7, which forms the inlet-aperture 8 of the pump, the outer end of this extension being desirably internally threaded, as indicated at 9, to receive the end of the suction-pipe 10, which communicates with the source of its supply. The end member or casting 3 is also provided with an axially-disposed extension 11, which is axially bored, as indicated at 12, and forms a journal-bearing and support for the actuating-shaft 13, upon the inner end of which is mounted the piston, (designated as a whole 14.) Upon the outer end of said shaft may be conveniently mounted a drive-pulley 15, by means of which the pump is actuated.

The cylindric shell member 4 is provided at a point intermediate its axial length and at one side thereof with a radially-extending tubular extension 16, which forms the outlet 17 of the pump-body, this extension being also desirably internally threaded to receive the end of the discharge-pipe 18.

It will be understood that the direction in which the pump is arranged to discharge, whether upwardly, downwardly, or to either side, is immaterial, and for that matter the pump need not be arranged horizontally, as shown, but may be arranged in any other position as found convenient or desirable.

Describing now more specifically the construction of the piston, this member as preferably constructed comprises two disk-like end members 19 and 20, respectively, and an interposed diaphragm 21, which constitutes in substance a pair of pallets or vane-like blades arranged in diametrically opposite relation. The end member 19 is provided with

an axially-disposed inlet-aperture, which is desirably somewhat larger than the inlet-aperture 8 of the pump-casing, so as to afford free entrance to the interior of the piston-shell. The opposite end member 20 preferably completely closes that end of the piston and is provided at its center with an inwardly-extending hollow boss or socket 22, with which is rigidly engaged the end of the actuating shaft 13, thereby supporting the piston accurately within the casing and preferably entirely free from contact with the inner walls of the latter. The internal diameter of the casing is somewhat greater than the external diameter of the piston, so as to afford an annular space 23 between said members, but the end walls of the casing are desirably constructed to fit as closely to the ends of the piston as is consistent with freedom of movement.

20 The diaphragm 21 is of peculiar and novel form, its construction being such in cross-section as to provide two spirally-disposed vanes or blades 24 and 25, united with each other by means of a reverse-curved portion 26, the spirals merging into the reversed-curved portion smoothly, so that there are thereby formed two spiral liquid passages 27 and 28, extending from the axial portion of the piston outwardly to the peripheries thereof, as shown clearly in Figs. 2, 3, and 4. The two vanes 24 and 25 desirably extend at their outer ends flush with the outer periphery of the piston, and a free discharge-passage 29 for the liquid is formed between the rear end of each vane and the rear side of the preceding vane, as best indicated in Fig. 2. In other words, the body of the piston is open at its sides, except to the extent it is closed by the spiral vanes or blades themselves.

30 In operation the pump-piston is rotated in the direction indicated by the arrow in Figs. 2, 3, and 4, or, in other words, in such a direction as to constantly present the convexly-curved portions 30, formed at the juncture of the spiral portions with the reversely-curved portions and the convex surface of the spiral portions 24 and 25 to the body of water within the pump. The rapid rotation of the piston therefore not only serves to impart a rotary movement to the liquid body, which creates a strong centrifugal force, but also serves to force the water outwardly positively after the manner of a propeller-blade. These two forces therefore act together to expel the liquid from the pump-casing and obviously to create a suction which correspondingly draws in the liquid from the sources of supply.

40 It is found in practice that a pump constructed in accordance with the present invention is extremely effective as a force-pump, enabling the water to be sent to great heights or against high pressures very effectively, while at the same time it is correspondingly effective in drawing or sucking in the liquid from a suitable source of supply.

It will be noted that the passages 27 and

28 are somewhat larger at the axial portion of the piston than elsewhere, or, in other words, contract outwardly, and this, coupled with the fact that the vanes are imperforate, 70 doubtless contributes in producing an effective exhausting action, since such a construction prevents the backflow or venting of air through the discharge-ports of the piston. It is further to be noted that the shape of the 75 diaphragm which forms the vanes is such that a minimum resistance to the passage of the diaphragm through the liquid is afforded consistent with imparting to the liquid the desired movement. In other words, a smoothly-80 rounded and obliquely-disposed surface is constantly presented to the body of water, and that portion of the opposing surface of the vane or blade which is most nearly radial is also nearest the axis of the piston, where 85 the movement of rotation is least. It results, therefore, that the pump may be driven with a minimum expenditure of power relatively to its pumping capacity.

It will be understood that the details of 90 construction may be considerably varied without departing from the invention, and I do not, therefore, limit myself to the details shown herein, except to the extent that they are made the subject of specific claim. 95

I claim as my invention—

1. In a centrifugal pump, the combination of a piston comprising a pair of disk-like end members, one of which is imperforate and the other provided with an axially-disposed inlet-port, a sheet-like diaphragm extending between said end members and folded or re-curved upon itself to form in cross-section two diametrically opposite spirally-curved pallet-blades each extending from the periphery of the piston inwardly toward the axis thereof, and an intervening portion uniting said spirally-disposed blades reversely curved in cross-section and the curves whereof merge smoothly into the curves of the blades, the passage-forming sides of said blades being outwardly convergent, a casing inclosing said piston, the internal diameter of which is greater than the exterior diameter of the piston whereby an intervening annular piston 100 is formed, an inlet through said casing in register with the end port of the piston, and an outlet in said casing communicating with the said annular space thereof. 105

2. In a centrifugal pump, the combination 110 of a piston comprising a pair of disk-like end members, one of which is imperforate and the other provided with an axially-disposed inlet-port, a sheet-like diaphragm extending between said end members and folded or re-curved upon itself to form in cross-section two diametrically opposite spirally-curved pallet-blades each extending from the periphery of the piston inwardly toward the axis thereof, and an intervening portion uniting 115 said spirally-disposed blades reversely curved in cross-section and the curves whereof merge 120

125

135

smoothly into the curves of the blades, the passage-forming sides of said blades being outwardly convergent, a casing inclosing said piston, the internal diameter of which is greater than the exterior diameter of the piston whereby an intervening annular space is formed, an inlet through said casing in register with the end port of the piston, and an

outlet in said casing radially opposite the periphery of the piston, substantially as described.

WILLIAM S. SHARPNECK.
